UNITED STATES PATENT OFFICE.

GEORGE H. COUPER, OF ELMIRA HEIGHTS, NEW YORK, ASSIGNOR TO ECLIPSE MACHINE COMPANY, OF ELMIRA, NEW YORK, A CORPORATION OF NEW YORK.

HACKSAW.

No. 925,684.

Specification of Letters Patent.

Patented June 22, 1909.

Application filed February 14, 1908. Serial No. 415,978.

To all whom it may concern:

Be it known that I, GEORGE H. COUPER, a citizen of the United States, and resident of Elmira Heights, in the county of Chemung and State of New York, have invented certain new and useful Improvements in Hack-saws, of which the following is a specification:

This invention relates to hack saw machines, and has for its object to produce a thoroughly efficient device of this character, which is comparatively simple in construction and unlikely to become disabled in operation.

In the drawings: Figure 1 is a front elevation of the machine at the end of the first stroke in sawing off a bar; Fig. 2 is a top plan view of the same; Fig. 3 is a front elevation showing the machine after the bar has been completely sawed through; Fig. 4 is an elevation of the outer end of the chuck, the cover-plate being removed; Fig. 5 is a section on the line 5—5 of Fig. 4; and Fig. 6 is a front elevation of a detail, certain parts being shown in dotted lines.

The machine has a base or standard 1, to which is fastened a frame 2 that supports in suitable bearings transverse shafts 3 and 4. The shaft 3 is revolved by means of a belt-wheel 5 keyed to its rear end, and the motion therefrom is transmitted to the shaft 4 through a pinion 6 that meshes with a gear 7 on the latter shaft. In the drawings, the direction of rotation of the shafts 3 and 4 is indicated by arrows. In the shaft 3 is a coupling or similar device 8, operated by a hand-lever 9, for the purpose of disconnecting the pinion 6 and the mechanism driven thereby from the pulley 5 when desired.

At the end of the base 1 opposite to the frame 2 is a bearing 10, in which is a revoluble barrel 11 (Fig. 5). On the front end of said barrel is formed a square frame 12 (Fig. 4) that is a holder or support for a series of wedge-faced blocks 13, 14, 15 and 16. These blocks and the containing parts constitute a chuck for gripping a bar of metal and holding it in a suitable position for sawing off. A screw 17 passes through the block 13, and by means of nuts 18, 18 is prevented from moving longitudinally, and therefore, when turned, said screw advances the block 13 to the left or right, as the case may be. If said block is moved toward the right (Fig. 4), the inclined face or edge 19 thereon, acting on

the inclined edge 20 of the block 14, forces the latter downward, and it, in a similar manner, causes the block 15 to move toward the left, and the block 16 to move upward. An opposite motion of the screw obviously produces an opposite effect, and the said blocks are thereby uniformly moved away from each other. Owing to the powerful wedging action of the blocks upon one another, a powerful grip may be obtained upon a bar of metal by applying a comparatively small amount of power to the screw. A plate 21, corresponding in size to the frame 12, is screwed to the front of the latter to prevent the blocks from falling out. The invention of this application does not include this specific form of chuck, and other forms are suitable for the machine.

At the rear end of the barrel 11 is a flange 22 that has a ratchet 23 upon its periphery. A pawl 24, adapted to engage said ratchet, is pivoted in a ring 25 that is revoluble upon said barrel. A rod 26 is connected at one end to the pivot 27 on which the pawl 24 is hung, and at the other end to a wrist-pin 28 that is set in a disk 29 on the shaft 4. As said shaft revolves (indicated by the arrow, Fig. 1), and the wrist-pin 28 passes over it, the pawl 24 is carried back upon the ratchet 23. As the said wrist-pin moves farther and passes underneath the shaft 4, the bar 26 pulls the top of the ring 25 toward the right, and the pawl 24, engaging a tooth of the ratchet 23, causes the latter, and therefore the chuck which is integral therewith, to partially revolve. The bar of metal X held in said chuck is thus intermittently turned in the direction of the arrow in Fig. 3 as the shaft 4 revolves.

Upon the bearing 10, near the front, are set two posts 30, 30, and a crosshead 31 is mounted upon these so as to be capable of vertical movement. Rigidly supported in said cross head are horizontal guide-rods 32, 32, upon which the saw-frame 33 is in turn mounted, so that the latter is horizontally movable to and fro. The posts 30, 30 may be braced as by 30^a from the frame 2. The saw frame 33 shown is substantially semicircular in form, and has lugs 34, 34 at its top, through which the rods 32, 32 extend. In the lower extremities of said frame are suitable set screws for fastening an ordinary hack saw 35. A weight 33^a is cast in the frame 11.

between the lugs 34, and serves to press the saw closely upon the work, and also steadies its motion.

A lever 36 is pivoted at 37 to one of the 5 posts 30, and is connected to the crosshead 31 by a link 38. Upon this a weight 39 may be hung, which to some extent counterbalances the saw-frame 33 and the crosshead 31. The said lever may also be extended to form 10 a handle 40 by means of which to raise and lower the saw-frame. When raised above the work for the purpose of adjusting the latter, the saw-frame and connected parts are retained in any desired position by means of 15 a dog 41 that is pivoted to the rear of the crosshead 31 and engages one of a series of notches 42 in a post 30. In order to lower the saw upon the work, the dog 41 may be disengaged by hand.

20 The saw-frame 33 is reciprocated horizontally by means of a pitman 43 that is pivoted to said frame at 44, and to the gear-wheel 7 at 45. The connection 45 is made adjustable by a slot 46 or otherwise, for the purpose 25 of adjusting the stroke of the saw 35.

The operation of the machine is as follows: The bar of metal X is clamped in the chuck jaws, while the saw-frame is in its elevated position; and the latter is lowered to the position shown in Fig. 1 by means of the handle 30 40. The clutch 8 being then thrown in by the lever 9, the saw is set in motion, the saw being held in contact with the work by the weight 33^a, and, if necessary, by additional 35 hand pressure applied through the lever 36. The rod 26, connected to the wrist-pin 28, pushes the pawl 24 over the teeth of the ratchet 23 while the pitman 43 moves the saw 35 toward the right which is the non- 40 cutting stroke of said saw). As the shaft 4 revolves further, the movement of the pitman 43 and the rod 26 are reversed, and the pawl 24 actuated by the latter engages the ratchet 23 and thereby turns the bar X

through part of a revolution, as before described. At this time the saw 35 is being carried toward the left by means of the pitman 43, and is cutting said bar. It will be seen that the bar X is thus revolved in a direction opposite to the cutting stroke of the saw, thus obtaining a greater cutting speed. A further advantage of this arrangement is that the length of the cut remains uniform as the saw progresses through the metal, because a fresh surface is turned into the path of the saw at every stroke of the rod 26. I also call particular attention to the fact that the pitman 43 is connected to the saw-frame 33 at such a point that the saw 35 is pulled instead of pushed across the bar X during the cutting stroke, thereby preventing the chattering which frequently occurs, and giving a more even stroke.

What I claim is:

A saw machine comprising a suitable 65 frame, vertical guides at one end thereof, parallel horizontal shaft bearings at the opposite ends thereof, a vertically sliding saw frame carrier mounted on said guides and provided in turn with longitudinally extending 70 guides, a saw frame having bearings sliding on said guides, a rotary chuck extending between said vertical guides and at its rear end provided with peripheral ratchet teeth, a loose ring alongside said ratchet teeth, a 75 pawl pivoted to the ring and engaging said teeth, a driven shaft mounted in one of said shaft bearings and having wrist pins or the like at its ends, connecting rods connecting said wrist pins with the pawl, and the saw 80 frame respectively, and a drive shaft mounted in the other shaft bearing and geared to the driven shaft.

GEORGE H. COUPER.
